DESIGN FOR A STROLLER

William C. Troendle, Gardner, Mass., assignor to Thayer Company, Gardner, Mass., a corporation of Massachusetts

Application February 13, 1940, Serial No. 90,233

Term of patent 3½ years

To all whom it may concern:

Be it known that I, William C. Troendle, a citizen of the United States, residing in Gardner, in the county of Worcester and State of Massachusetts, have invented a new, original, and ornamental Design for a Stroller, of which the following is a specification, reference being had to the accompanying drawing, forming part thereof.

Fig. 1 is a perspective view of a stroller illustrating my new design; and

Fig. 2 is a plan view.

I claim:

The ornamental design for a stroller, substantially as shown.

WILLIAM C. TROENDLE.
